UNITED STATES PATENT OFFICE.

BAGSTER R. SEABROOK AND FRANK C. PRIESTLY, OF LOS ANGELES, CALIFORNIA, ASSIGNEES, BY DIRECT AND MESNE ASSIGNMENTS, TO AMERICAN DIFFERENTIAL RAILWAY AXLE COMPANY, OF LOS ANGELES, CALIFORNIA, A CORPORATION OF ARIZONA TERRITORY.

DIFFERENTIAL AXLE DEVICE.

No. 891,958.

Specification of Letters Patent.

Patented June 30, 1908.

Application filed September 30, 1907. Serial No. 395,110.

To all whom it may concern:

Be it known that we, BAGSTER R. SEABROOK, a subject of Great Britain, and FRANK C. PRIESTLY, a citizen of the United States, both residing at Los Angeles, county of Los Angeles, State of California, have invented new and useful Improvements in Differential Axle Devices, of which the following is a specification.

10 Heretofore in differential axle devices it has been customary to connect the parts of the axle by means of a box or jacket, the parts of which were secured together by means of bolts, screws or rivets. In this 15 construction, however, where the differential axle was subjected to any constant jarring strain such as is put upon an axle used for cars, the constant jarring to which the same is subjected would cause the bolts, 20 screws or rivets to become loose, and would also cause the bolts, screws or rivets to crystallize so that the parts of the box were liable to become separated or deflected by reason of the nuts coming off or the bolts, screws or 25 rivets breaking, thereby rendering the device unsafe.

It is the object of our invention to connect the parts of the axle without the use of bolts, screws or rivets, and in such manner that the 30 usual jar upon such an axle, when used for railway purposes, does not have any effect upon the members of the box which connects the parts of the axle to cause them to accidentally separate, or to crystallize and to 35 break.

Another object is to provide a box so constructed that by the use of appropriate appliances, applied directly to the members comprising the box the same can be separated when desired, so that a portion of the 40 axle can be removed, should the same become accidentally broken, or should the same become worn out, without interfering with the other portion of the axle.

45 We accomplish these objects by the device described herein and illustrated in the accompanying drawings which show our invention applied to the axle of a railway car, the wheels and axle being shown in elevation 50 and the box or coupling device shown in section.

In the drawings 1 are the car wheels which are secured upon the axle 2 in the usual

manner. The axle is cut in two at 3. The parts 2^a and 2^b of the axle are secured together by means of the coupling device which consists of a sleeve 4 which is secured upon the inner part of the portion 2^b of the axle by being forced thereon by hydraulic, or other pressure. Beyond the inner end of 60 the part 2^b of the axle sleeve 4 is bored out so as to chamber the annular securing ring 5 which is secured upon the inner end of the part 2^a of the axle. The extreme inner end of the part 2^a of the axle is reduced in size so 65 as to pass through the bore of the annular ring 5 when suitable pressure is applied thereto, and the inner end after passing slightly through this annular ring is headed down upon the ring so as to prevent its coming off. We prefer to put this annular ring upon the end of this portion of the axle by great pressure so as to still further secure the same thereto before the same is riveted. If desired, however, the reduced portion of this 75 axle could be exteriorly threaded and the ring interiorly threaded and the ring secured to the axle by being screwed thereon before being riveted or it could be screwed therein and frozen thereto. The parts can also be 80 secured together by one part being shrunken on the other.

The annular securing ring is preferably of a greater diameter than the axle, and that portion of the axle to which the same is 85 secured is preferably reduced in size where it passes through sleeve 6, as shown in the drawings. The inner end of sleeve 6 is preferably reduced in size so as to be able to be forced by hydraulic pressure or other 90 pressure within the sleeve 4 until the shoulder 7 thereof engages the end of sleeve 4, and at the same time the inner end of sleeve 6 engages the securing ring 5 in working contact therewith. Near the outer end of 95 sleeve 6 the axle is preferably enlarged to form a shoulder 8 and the sleeve is correspondingly enlarged at this point. The object of this construction is to make a break near the outer end of the sleeve in the line of engagement between the sleeve and this portion of the axle to provide what we call a dust joint at the outer end of the sleeve, between the sleeve and the axle and to prevent movement of the sleeve toward the 100 wheel.

105

Sleeve 6 is provided with an annular ledge 9 and sleeve 4 is provided with a like annular ledge 10 that proper appliances may be secured upon the ends of the sleeve so that 5 the sleeves 4 and 6 may be forced apart in case it is desired to replace either of the parts 2^a or 2^b. The inner end of the part 2^b of the axle is reduced in size to form a shoulder 11 and where it enters the sleeve it is likewise 10 reduced in size to form a shoulder 12, and the sleeve is of a configuration to fit upon the end of this portion. These shoulders are provided to prevent any outward thrust 15 of the sleeve 4. Sleeve 4 is provided with lubricant ports 13 and 14 and internal lubricant grooves 15 and 16. Lubricant groove 15 is in register with port 17 in sleeve 6. Sleeve 4 is likewise provided with longitudinal lubricant channels 18 and 19 which 20 are connected at one end with the internal groove 15, so that proper lubricant can be supplied to the rotating parts.

By this construction it will be observed that by the use of sufficient pressure, by 25 means of hydraulic or other apparatus the securing ring can be fastened upon one part of the axle, the parts of the sleeves secured together and upon the other part of the axle so as to produce the necessary resistance 30 against separation of the parts, whereby the parts of the axle are secured together without the use of bolts, screws or rivets, thereby making a self-contained bearing which cannot be affected by the ordinary jar, and the 35 parts of which cannot accidentally become separated, and at the same time the parts are so secured together that if desired by the use of appropriate mechanism, the same can be disassembled. It will be observed that 40 either car wheel can rotate independently of the other wheel on the same axle, thereby preventing friction in turning curves or when there is any inequality in the surface of the

rails upon which the wheels run, and to provide for inequality in the diameters of the 45 wheels.

Having described our invention what we claim is:

1. A differential axle device mechanism comprising a box formed of telescopic parts, 50 said box having an internal groove, one portion of said box being loosely passed upon the inner end of one portion of the divided axle, and the other portion of the box being secured upon the inner end of the other portion of the divided axle; a securing ring secured upon the inner end of that portion of the divided axle which is loosely passed through a portion of the box after the end of the axle has been passed through such portion of the box, said two portions of the box being then united by frictional engagement effected by great pressure.

2. In a differential axle device a self-contained coupling box having the parts telescopedically secured together by means of the frictional engagement of such parts.

3. In a differential axle device a self-contained coupling box having telescopic parts secured together by pressure and having 70 ledges on the ends thereof whereby the same can be separated when desired, substantially as and for the purpose specified.

4. In a differential axle device a self-contained coupling box having the parts telescopedically secured together by means of the frictional engagement of such parts; and having lubricating ports and channels therein.

In witness that we claim the foregoing we have hereunto subscribed our names this 80 19th day of September, 1907.

BAGSTER R. SEABROOK.

FRANK C. PRIESTLY.
